UNITED STATES PATENT OFFICE

DAVID CRAWFORD, OF ATLANTA, GEORGIA.

SWING.

1,135,160.

Specification of Letters Patent. Patented Apr. 13, 1915.

Application filed June 30, 1914. Serial No. 848,230.

To all whom it may concern:

Be it known that I, DAVID CRAWFORD, a citizen of the United States, residing at Atlanta, in the county of Fulton and State 5 of Georgia, have invented certain new and useful Improvements in Swings; and I do hereby declare the following to be a full, clear, and exact description of the invention, such as will enable others skilled in 10 the art to which it appertains to make and use the same.

This invention relates to swings, and the primary object of the invention is the provision of a swing specially constructed, 15 whereby the swing may be moved in an oscillatory or swinging movement by a person seated therein.

Another object of this invention is the provision of a swing as specified which has 20 a hinged foot tread, which foot tread is connected to a lever and carried by the swing, and the lever is in turn connected to a part of the suspending rope or chain of the swing, so that when the foot tread is moved 25 in an oscillatory manner, the lever arm will be operated for moving the suspending cables or chains, thereby imparting an oscillatory movement to the swing.

With the foregoing and other objects in 30 view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in 35 which:

Figure 1 is a side elevation of the improved swing, Fig. 2 is a front view of the swing, and Fig. 3 is a fragmentary view in rear elevation of a portion of the swing.

Referring more particularly to the drawings, 1 designates the swing body as an entirety, which is composed of a base or platform 2 having the vertically upstanding front supports 3 and 4 secured thereto, and 45 the vertically extending back supports 5. A seat 6 is positioned within the swing, and extends transversely therein, as is ordinary in the construction of swings of this nature, and a back 7 is pivotally connected to 50 the seat 6, and is held in various adjusted inclined positions, to accommodate the con-

venience of the person seated in the swing, by bars 8, which extend along the sides of the swing and to which the back is adjustably connected by means of bolts or the like 60 which are inserted through any one of the openings 9, which are formed in the bars 8.

The forward end of the foot board or platform 2 has a foot treadle 10 hingedly connected thereto as is shown at 11. The 65 foot treadle 10 extends across the width of the swing and has cables or chains 12 secured to its opposite ends adjacent its free marginal edge as is clearly shown in Fig. 1 of the drawings. The chains or cables 12 pass upwardly from the foot treadle and over pulleys 14, which pulleys are supported by the sides of the swing, and the cables extend transversely across the swing, having 70 their terminal ends secured to eyelets 15, 75 which are formed upon the upper terminal ends of levers 16. The levers 16 are swivelly connected at their lower terminal ends, to blocks 17, which blocks are formed upon the swing construction, and the levers are 80 movable in an arch about their swiveled connections. The levers 16 have eyelets 18 secured to their rear sides intermediate of the ends, to which the swing suspending cables or chains 19 are connected.

The front or forward end of the swing is 85 pendently supported by the swing supporting cables 20, which are secured to the sides of the swings in any suitable manner as is shown in Figs. 1 and 2 of the drawings.

In the operation of the improved swing: a person seated upon the seat 6 of the swing, moves the foot treadle 10, in an oscillatory manner, pressing downwardly upon the foot treadle which downward pressure thereupon will draw the cables or chains 12 downwardly, and forwardly, rocking the lever 16 and moving it forwardly, which in turn rocks the swing suspending cables 19, causing them to impart a swinging 95 movement to the swing 1. When the foot treadle has been compressed to the limit of its downward movement, the quick upward movement of the feet therefrom, or the relieving of the pressure from the foot 100 treadle and the pressure of the body or weight of the person against the back of the swing, will move the foot treadle to its normal position as well as the lever 16, moving the suspending cables 19 rearwardly. 105 By continuation of this operation, the momentum of the swing may be increased un-

til the desired speed of swinging motion is obtained.

In reducing the invention to practice, certain minor features of construction, combination and arrangement of parts may necessitate alterations to which the patentee is entitled provided such alterations are comprehended within the scope of what is claimed.

10 What is claimed is:

In a swing structure, a swing comprising a base platform, vertically extending sides and back secured to said base platform, a transversely extending seat supported within said sides, flexible cables for swingably suspending said swing structure, a foot treadle hingedly connected to the forward

20 marginal edge of said base platform, a plurality of levers swivelly connected to the back of said swing structure adjacent the sides thereof, said levers being connected to said swing suspending cables, and flexible members connecting said foot treadle and said levers whereby said levers will be oscillated upon oscillatory movement of said foot treadle for imparting swinging motion to said swing.

25 In testimony whereof I affix my signature in presence of two witnesses.

DAVID CRAWFORD.
